PRINTING TELEGRAPH APPARATUS

Albert H. Reiber, Evanston, Ill., assignor to Teletype Corporation, Chicago, Ill., a corporation of Delaware

Application July 14, 1934, Serial No. 735,094

24 Claims. (Cl. 178—25)

The present invention relates to printing telegraph apparatus and more particularly to improvements in tabulating mechanisms therefor.

It is the principal object of this invention to provide an efficient and smoothly operating tabulating mechanism selectively responsive to code combinations of signalling impulses for controlling tabulation recording.

A feature of the invention resides in enhancing the speed of movement of the type carriage in effecting the tabulating function, during which operation the type carriage will be spaced continuously at a speed which is three times that of normal spacing.

15 The above and other objects of the present invention are accomplished by the provision in a printing telegraph apparatus of a tabulator bar which extends across the front of the machine and is pivotally carried by brackets and capable 20 of swinging toward and away from the type carriage. The tabulator bar carries a number of adjustable stop members which determine the 25 positions at which the type carriage comes to rest after spacing during the tabulating cycle. The spacing mechanism of the printing apparatus 30 comprises a three-toothed ratchet adapted to cooperate with a pair of pawls which are actuated by the printing bail to function as an escapement mechanism so that, upon each revolution 35 of the main shaft, the spacing worm gear associated with the spacing ratchet is permitted to rotate one-third of a revolution.

A series of function levers is provided which 40 operate selectively in accordance with the setting 35 of a series of selector vanes. Among the function levers of this series is a tabulating function lever which, when selected, is drawn forward under spring tension. When this occurs, the rear extension of the function lever rises and thereby 45 lifts the rear end of a horizontal member. When the rear end of this horizontal member is lifted, it lifts the upper space pawl out of engagement 50 with the tooth of the spacing ratchet, at which time the front end of said horizontal member is lowered thereby unlatching the tabulating bar to permit the latter to be rotated by its spring 55 toward the type carriage. When the upper space pawl is thus disengaged, the lower space pawl remains in its normal position entirely free of the teeth on the escapement ratchet, thus permitting the spacing worm gear to make one 60 complete revolution instead of only one-third of a revolution during the time that the main shaft rotates through one revolution, and therefore the 65 carriage will be spaced continuously a distance

per revolution of the main shaft which is three times that of normal spacing distance. To bring the carriage to rest after tabulating it is necessary to permit the upper space pawl to drop again into engagement with a tooth on the spacing ratchet. This latter function is effected by the cooperation of a cam element assembled to the carriage and one of the adjustable stop members carried by the tabulator bar. This cam forces or cams the tabulator bar forward or 5 away from the carriage, against spring tension, and in doing so permits said horizontal member to be restored to its normal position into latching engagement with the tabulator bar. This restoration action of the horizontal member permits the upper space pawl again to fall into engagement with a tooth on the spacing worm ratchet, which thereupon brings the carriage to rest.

A better understanding of the invention may 20 be had from the following description taken in conjunction with the accompanying drawings wherein,

Fig. 1 is a partial front elevation of the printing apparatus showing the application of the 25 tabulating mechanism thereto;

Fig. 2 is a perspective view of the tabulating mechanism applied to said printing apparatus;

Fig. 3 is a transverse cross-sectional view of the printer taken approximately through the 30 vertical center line of Fig. 1;

Fig. 4 is a sectional view taken on line 4—4 of Fig. 3;

Fig. 5 is a detail rear elevation of the spacing 35 mechanism of the printing apparatus; and

Fig. 6 is a sectional plan view of the spacing mechanism.

In the accompanying drawings like reference characters indicate similar parts throughout. For a complete understanding of details not disclosed herein and which form no part of the present invention, reference may be had to the U. S. Patent No. 1,904,164 issued April 18, 1933 to S. Morton et al.

Briefly, having reference to Figs. 1, 3, and 6, a printing apparatus to which the tabulating mechanism of the present invention is applied comprises a typing unit (shown generally in section in Fig. 3) which includes a primary selecting mechanism indicated generally as 11 (Fig. 6) 45 which is of the sword-and-T type disclosed in U. S. Patent No. 1,745,633 to S. Morton et al. (fully disclosed in the first mentioned patent), and a secondary selector or selector vane assembly indicated generally as 12. The selector 50

55

vane assembly 12 controls through a series of bell cranks 13 (Fig. 1) a corresponding series of curved code bars 14 carried in a movable type carriage. As set forth in the first mentioned 5 patent, this type carriage, indicated generally as 15, is movable longitudinally in respect to a stationary platen indicated generally as 16 (Fig. 3). The type carriage 15 also carries a ribbon feed mechanism indicated generally as 17.

10 Referring particularly to Fig. 6, a motor 18 supplies power through gear 19 to a main operating shaft 21 which carries the spacing mechanism indicated generally as 22 and the selector cam assembly indicated generally as 23.

15 As is known in this type of device, power is communicated from the motor to an operating cam assembly through a grab clutch such as 25. Pinned portion 24 of grab clutch 25 constantly rotates with the shaft 21, which has also frictionally connected thereto the spacing mechanism 22 and the selecting cam assembly 23. Portion 24 is cooperatively engaged with the splined portion 26 when throw-out lever 27 is operated in timed relation with the reception of 25 code signals.

The spacing mechanism 22, which will be described more in detail hereinafter, controls through gear 28, shaft 29, gear 31, and rack 32 (Fig. 3), the movement of type carriage 15 to 30 form character spaces, tending in this movement to wind up the carriage return spring mechanism indicated generally as 33. Upon receipt of the carriage return signal, function bar 34 is actuated selectively in the manner described in 35 Patent No. 1,904,164 so as to permit spring 35 to rotate lever 36 suddenly against stop 37 to raise, through bell crank 38, portion 39 of grab clutch 41. Carriage return mechanism 33 is thereupon permitted, due to the energy stored up therein, 40 to return the carriage 15 to its normal or beginning-of-line position.

Positioned parallel to the main operating shaft 21 is a rocking shaft 42 on which are carried various mechanisms, for example, printing bail 43, 45 function bail 40 and the escapement mechanism for the spacing mechanism 22. The printing bail 43, which is actuated by a printing spring (not shown) in proper timed relation in the operative cycle, functions to reciprocate a pull bar operating member 44 to cause the operation of a type bar, as clearly described in the aforementioned patent.

The selector vanes as set forth in Patent No. 1,904,164 control a series of function levers among 55 which are provided especially for accomplishing the object of the present invention is a tabulating function lever 45 which like the other function levers is pivoted on a common pivot rod 46 and is assembled in a slot in the function lever comb 60 47. This function lever 45, like the rest of the function levers of the series, is provided with an individual spring 48 tensioned between it and the printer frame which tends to rotate the function lever 45 about pivot 46 but, as clearly set forth 65 in Patent No. 1,904,164, is restrained by the function lever bail 40 acting through rod 50 on arm 60.

Before describing further the function of lever 45, a detailed description of the spacing mechanism will be given. Having reference to Figs. 3 70 and 5 there is shown mounted on the main shaft 21 and located centrally of the apparatus a sleeve member 51 which comprises escapement ratchet 52 and escapement worm 53 which are integral therewith. Sleeve member 51 is operably connected to the hub of a disc 54 by means of inter-

engaging tongue and groove members 55. Collar 56 is pinned to main shaft 21 and is rotatable therewith. Interposed between disc 54 and collar 56 is disc 57 of frictional material, for example, felt. By means of a helical compression spring 58, which exerts a thrust tension between disc 57 and a pinned collar sleeve 51 is frictionally connected to shaft 21 through the friction clutch comprising members 54, 56, and 57. Sleeve 51 is thereby rotatable with main shaft 21 unless arrested by the escapement pawls of the spacing mechanism 22 as will presently appear.

Referring to Fig. 3 it will be noted that ratchet 52 is provided with three teeth or notches 61, 61a, and 61b, the escapement of which will allow 15 the type carriage 15 to be moved forward one step or character space for each actuation of the printing bail 43. As indicated, the escapement mechanism comprises levers 62 and 63, pivotally mounted on bail shaft 42, and lever 64 adjustably 20 fixed to printing bail 43. Spring 65 normally tends to rotate levers 62 and 63 in opposite directions, since it is common to both levers. Lever 62 is normally urged by spring 65 in a counterclockwise direction so that laterally disposed end 25 66 engages tooth 61 of ratchet 52, thus arresting the rotation of said ratchet. Lever 63 is normally held out of engagement with ratchet 52 against the tension of spring 65 by the action of lever 64 against laterally disposed end 67.

Lever 64 is pivotally connected to printing bail 43 at 68 and is provided at 69 with a slot and screw adjusting means, whereby the correct relative position of escapement levers 62 and 63 with respect to ratchet 52 may be determined. The 35 spacing operation occurs immediately following or subsequent to the printing of a character in the following manner.

Upon the printing of a character, lever 64 is caused to rotate slightly in a clockwise direction 40 with printing bail 43 which moves clockwise about the axis of bail shaft 42, thereby transferring this motion to lever 62 through its laterally disposed end 71, tripping its end 66 out of engagement with tooth 61 and permitting ratchet 52 to 45 rotate slightly in a clockwise direction under the influence of friction clutch members 54 to 57 (Fig. 5) until arrested by the engagement of tooth 61a with laterally disposed end 72 of lever 63 which lever by movement of lever 64 was rendered free to rotate in a clockwise direction under the tension of spring 65 into the path of oncoming tooth 61a. Ratchet 52 is thus restrained from rotation by lever 63 until the completion of 55 the printing of a character at which time printing bail 43 and associated lever 64 are caused to rotate in the opposite direction by the action of a printing cam (not shown). Restraint of lever 62 by lever 64 through end 71 is thereby removed, permitting lever 62 to rotate in a counterclockwise direction under the influence of spring 65 60 into the path of tooth 61b of ratchet 52. During this counterclockwise movement of lever 64, and immediately after the aforementioned release of lever 62, lever 63 is caused to rotate in a like 65 direction due to the action of lever 64 on end 67 thereof, thereby disengaging end 72 of lever 63 from tooth 61a and allowing ratchet 52 to 70 continue its rotation until arrested by the engagement of end 66 of lever 62 with tooth 61b.

It is obvious that since worm 53 and ratchet 52 are integrally connected to sleeve 51, said worm 53 will have normally the same intermittent or step-by-step motion as was hereinbefore seen to be imparted to ratchet 52. Worm 53 is meshed 75

with worm gear 28 (Figs. 3 and 6) which is loosely mounted on vertical shaft 29, and is operably connected thereto by means of jaw clutch 41. Worm 53 and gear 28 are so related that one-third 5 revolution of worm 53 will rotate gear 28 through a distance which, through gear 31 and rack 32, causes the type carriage to be stepped forward one character space.

From the foregoing it will be observed that 10 character spacing takes place automatically with the printing of each character; that is, the spacing function is merged into the printing operation. It is well known that there is a code combination allotted to each type bar; but it is possible, 15 however, to employ a code combination, commonly known as the spacing signal, which is identified with no type bar but which will nevertheless initiate the printing operation. Therefore the spacing between words is accomplished in exactly 20 the same manner as set forth when a spacing signal is received, except that no type bar is operated and consequently no character is printed.

In accordance with the present invention, continuous spacing may be effected upon the receipt 25 of a code combination known as the tabulating code combination which functions to initiate the operation of the tabulating mechanism.

The mechanically operated tabulating arrangement of the present invention comprises a 30 tabulator bar 81 extending across the front of the printing apparatus, as shown in Fig. 1, which is provided with depending portions 82 and 83 through which bar 81 is pivotally mounted on bracket 84 carried in the printer frame. Thus 35 tabulator bar 81 is adapted to be swingable toward and away from the type carriage 15. Bar 81 is also provided with a longitudinal slot 85 extending substantially the entire length of the bar. In this slot are adjustably movable stop members 40 86 which are adapted to be clamped to the bar 81 by means of screws 87 and clamps 88 individual to each stop member 86 (Fig. 3). As indicated in Fig. 6, these stop members 86 are each provided with an inclined or cam portion 89, specially conformed so as to provide a quick action 45 upon cooperation with a cam element 111 carried by the type carriage, to terminate suddenly the tabulating operation.

Tabulator bar 81 is also provided, intermediate 50 the depending portions 82 and 83 (Fig. 1) and suitably positioned relative to function lever 45, with another depending portion 91. Attached to and depending from portion 91 is a bar 92 the lower end of which is provided with an aperture 55 93 having its upper left-hand corner (as viewed in Fig. 3) conformed so as to provide a reentrant stepped portion 94. The tabulator bar 81, as indicated in Fig. 6, normally tends to move toward the printing apparatus due to the action of a 60 spring 95.

Cooperating with the stepped portion 94 is one 65 arm 96 of a lever 97 pivotally carried at 98 on a support 99 secured to the function lever comb 47. The extremity of arm 96 is provided with a laterally disposed portion 101 as shown in Fig. 4 which cooperates with portion 94 of member 92. At the end of arm 102 of lever 97 is rigidly carried a vertically extending member 103 the upper end 70 of which is provided (in the present embodiment) with an open-ended slot adapted to engage a pin 104 carried by escapement lever 62.

Function lever 45 is provided with a horizontal 75 portion 105 so conformed that its extremity 106 engages the lower edge of arm 102 of lever 97

such that when function lever 45 is permitted to rotate in a clockwise direction under the action of its spring 48 upon the proper setting of the vanes 107 in response to the tabulation code signal, the end 106 thereof is elevated, causing lever 97 to rotate slightly in a clockwise direction against the tension of its spring 108. The end 101 of arm 96 is thus moved downwardly, clear of portion 94, thus permitting spring 95 to urge the tabulator bar 81 inwardly (or toward the left as viewed in Fig. 3) until wall 109 of member 92 engages lug 101. The series of adjustable stops 86 are thus moved inwardly into the path of a cam member 111 pivoted at 112 on a portion 113 integrally formed on a bar 115 which is comparable to bar 53 shown in Fig. 1 of Patent No. 1,904,164 employed for retaining the bell crank levers 13 in operable relation to vanes 107. Thus cam 111, like bar 115 and bell cranks 13, is movable with the type carriage 15 for character spacing. Cam 111 normally tends to rotate in a clockwise direction about pivot 112 due to the action of spring 116, but its clockwise rotation is limited by the coaction of a stop pin 117, carried thereon, with the end of bar 115. Thus, upon the rightward movement of type carriage 15, cam 111, due to its non-rotatability in a clockwise direction, will, by its camming action on any stop member 86, actuate tabulator bar 81 outwardly; but upon the leftward movement of type carriage 15, cam 111 if striking any of the series of stop members 86 will be rotated counterclockwise against the action of spring 116 sufficiently to pass the cam portion 89.

Upon the clockwise rotation of lever 97 due to the selection of function lever 45, arm 102 and consequently portion 103 carried thereon will be raised and in so doing will, through pin 104, lift escapement lever 62 out of engagement with the teeth of the ratchet 52 which, since the lever 63 is prevented from engaging the teeth of the ratchet 52 due to its being held in inoperative position by lever 64, permits the worm gear to make one complete revolution instead of one-third of a revolution during the time that the main shaft rotates through one revolution, and therefore the carriage will be spaced continuously a distance per revolution of the main shaft which is three times that of normal spacing so long as the escapement lever 62 is held out of operative engagement with ratchet 52, which, as we have seen, is maintained in this position due to the engagement of lug 101 with the under side of step portion 94. Thus carriage 15 will be moved continuously until cam 111 cooperates with one of the series of stops 86, when cam 111 through stop 86 will urge tabulator bar 81 outwardly, as viewed in Fig. 6 (or in a clockwise direction as viewed in Fig. 3), the effect of which is to disengage lug 101 from portion 94, whereupon lever 97 will again be rotated in a counterclockwise direction by its spring 108 into the position shown in Fig. 3, in which event portion 103 carried on arm 102 of lever 97 will again be lowered, permitting escapement lever 62 under action of spring 65 to engage one of the teeth 61, 61a, or 61b of the ratchet 52.

The function lever 45, however, will have been 70 returned to its non-selective position, as shown in Fig. 3, at the completion of the first revolution or cycle of operation of the main shaft 21 by the return stroke or upward movement of shaft 50, where the lever 45 will be held in 75

operative until the reception of another tabulation code signal, pursuant to which the foregoing cycle of operations will again occur.

Obviously, changes may be made in the details set forth without departing from the essentials of the invention or from the spirit and scope of the invention as defined in the following claims.

What is claimed is:

- 10 1. In a recorder, selector mechanism responsive to received code combinations of signaling impulses, a type carriage movable normally one character space for each recording operation, and means controlled by said selector mechanism for causing said carriage to advance uninterruptedly through a plurality of spaces at a time from one recording position to another.
- 20 2. In a recorder, a carriage movable to form character spaces, means to perform functions other than recording, a permutation device movable with said carriage to determine the character to be recorded, a stationary permutation device to control said means and said permutation device, and a tabulating device controlled by said means for releasing said carriage for advancement through a plurality of spaces at a time from one recording position to another.
- 30 3. In a telegraph printer, a carriage movable to form character spaces, spacing mechanism therefor normally adapted to control the advancement of said carriage one character space for each printing operation, permutation code mechanism to control operations other than recording comprising a plurality of function code levers, and tabulating mechanism operative in response to the selective operation of a certain one of said levers to release said carriage for uninterrupted movement through a predetermined plurality of character spaces at a time.
- 40 4. In a telegraph recorder, a carriage movable to form character spaces, a spacing mechanism therefor normally adapted to control the advancement of said carriage one character space upon each operation thereof, said spacing mechanism comprising a pair of spring-biased pawls acting to afford an escapement therefor, permutation code mechanism to control operations other than recording comprising a plurality of function code levers, and tabulating mechanism operative in response to the selective operation of a certain one of said levers to effect, through the instrumentality of said lever, the disablement of one of said pair of pawls to release said carriage for advancement continuously through a plurality of spaces at a time.
- 50 5. In a telegraph recorder, a carriage movable to form character spaces, spacing mechanism therefor normally adapted to control the advancement of said carriage one character space upon each operation thereof, said spacing mechanism including a spacing ratchet, a pair of pawls and a single spring means to render said pair of pawls coercive with said ratchet in escapement manner, permutation code mechanism to control operations other than recording comprising a plurality of function code levers, and tabulating mechanism operative in response to the selective operation of a certain one of said levers to effect, through the operation of said lever, the disengagement of one of said pair of pawls to release said carriage for advancement continuously through a plurality of spaces at a time.
- 60 6. In a telegraph recorder, selector mecha-

nism responsive to code signals, a carriage movable to form character spaces, spacing mechanism therefor normally adapted to control the advancement of said carriage one character space upon each operation thereof, said mechanism embodying an escapement device including a pair of pawls and means to bias said pawls attractively, and tabulating mechanism effective under control of said selector mechanism to disable one of said pair of pawls to release said carriage for advancement continuously through a plurality of spaces at a time.

7. In a telegraph recorder, a carriage movable to form character spaces, spacing mechanism therefor normally adapted to control the advancement of said carriage one character space upon each operation thereof, said mechanism embodying an escapement device including a pair of pawls and means to bias said pawls attractively, permutation code mechanism to control operations other than recording comprising a plurality of function code levers, and tabulating mechanism operative in response to the selective operation of a certain one of said levers to disable, through the operation of said lever, one of said pair of pawls to release said carriage for advancement continuously through a plurality of spaces at a time.

8. In a telegraph recorder, a carriage movable to form character spaces, spacing mechanism therefor normally adapted to control the advancement of said carriage one character space upon each operation thereof, said mechanism embodying an escapement device including a pair of pawls and means to bias said pawls attractively, permutation code mechanism to control operations other than recording comprising a plurality of function code levers, and a tabulating mechanism comprising a pivotally mounted stop plate, a manually adjustable stop member adapted to be positioned at any one of a plurality of points along said stop plate, a projection on said carriage cooperable with said positioned stop member, and a depending latch portion coercive with an extension on one of said code levers, said tabulating mechanism operative in response to the selective operation of said extension carrying code lever to disable one of said pair of pawls to release said carriage for advancement continuously through a plurality of spaces at a time.

9. In a telegraph recorder, a carriage movable to form character spaces, means comprising a multi-toothed disc, the number of teeth being equal to the number of spacing operations per revolution of said disc, to effect said spacing movement, a bail movable in a complete cycle for each character spacing operation, detent means mounted in said bail whereby the movement of said bail during each spacing operation causes the escapement of said disc to effectuate, through said first-recited means, the spacing movement of said carriage, permutation code mechanism to control operations other than recording comprising a plurality of function code levers, and tabulating mechanism operative in response to the selective operation of a certain one of said levers to disable, through the operation of said lever, said detent means to enable said first-recited means to advance said carriage continuously through a plurality of spaces at a time.

10. In a telegraph recorder, signal responsive means, a carriage movable to form character spaces, means comprising a multi-toothed disc, the number of teeth being equal to the number

- of spacing operations per revolution of said disc, to effect said spacing movement, a bail movable in a complete cycle for each character spacing operation, detent means comprising a pair of attrahently biased pawls mounted in said bail whereby the movement of said bail during each spacing operation causes the escapement of said disc to effectuate, through said pair of pawls, the spacing movement of said carriage, and tabulating mechanism effective under the control of said signal responsive means to disaffect said pair of pawls to enable said second-recited means to advance said carriage continuously through a plurality of spaces at a time.
11. In a telegraph recorder, a single magnet responsive to received code combinations of impulse conditions, a plurality of recording elements, a plurality of selecting members controlled by said magnet for selectively operating said elements, guiding and supporting means, a carriage mounted for reciprocation on said guiding and supporting means, said elements and members being mounted on said carriage, a rack mounted on said carriage, a driven spacing worm cooperable with said rack, spacing mechanism for actuating said worm normally in a step-by-step manner to effect character spacing of said carriage, means responsive to said magnet comprising a plurality of function code levers for controlling operations other than recording, and tabulating mechanism operative in response to the selective operation of a certain one of said levers to disable said spacing mechanism to release said carriage for advancement continuously through a plurality of spaces at a time.
12. In a telegraph printer, signal responsive means, a movable carriage, a constantly rotating shaft, means constantly engaged by said shaft tending to continually advance said carriage, detent means comprising a pair of attrahently biased pawls normally preventing advance of said carriage, a periodically operable member, means controlled by said member for releasing said detent means to allow advance of said carriage one character space during each cycle of movement of said member, and tabulating mechanism effective under the control of said signal responsive means to disable one of said pawls to release said carriage for advancement continuously through a plurality of spaces at a time.
13. In a telegraph recorder, signal responsive means, means to effect recording operations, single means operable in cycles to actuate said means to effect character spacing, means comprising a pair of spring-biased pawls to limit the movement of said recording means to a single character space for each cyclic operation of said cyclically operable means, and means controlled by said signal responsive means to disable one of said pawls to allow advance of said recording means a plurality of character spaces for each cycle of operation of said cyclically operable means.
14. In a telegraph recorder, signal responsive means, means to effect recording operations, single means operable in cycles to actuate said means to effect character spacing, escapement mechanism comprising a pair of attrahently biased pawls normally adapted to advance said recording means one character space for each cyclic operation of said cyclically operable means, and means controlled by said signal responsive means to disable one of said pawls whereby said recording means is advanced a plurality of character spaces for each cycle of operation of said cyclically operable means.
15. In a telegraph printer, signal responsive means, a carriage movable to form character spaces, spacing mechanism comprising a pair of attrahently biased pawls normally adapted to control the advancement of said carriage one character space for each printing operation, single means operable in cycles to actuate said spacing mechanism normally one character space for each cyclic operation of said cyclically operable means, and means controlled by said signal responsive means to disable one of said pawls whereby said carriage is advanced a plurality of character spaces for each cycle of operation of said cyclically operable means.
16. In a telegraph recorder, signal responsive means, a carriage movable to form character spaces, a main shaft, an operating bail, a spacing mechanism associated with said shaft adapted to space said carriage a definite number of spaces during each revolution of said shaft, an escapement mechanism comprising a pair of attrahently biased pawls associated with said spacing mechanism and said shaft controlled by said operating bail to limit to one character space the movement of said carriage at each spacing operation, and means controlled by said signal responsive means to disable one of said pawls to render said spacing mechanism effective to advance said carriage continuously from one recording position to another.
17. In a telegraph printer, signal responsive means, a movable carriage, a constantly driven member, means engaged by said member tending to advance said carriage continually, detent means comprising a pair of attrahently biased pawls normally preventing advance of said carriage, an intermittently operable printing member, means controlled by said printing member for releasing said detent means to allow advance of said carriage only one character space during each cycle of movement of said member, and means controlled by said signal responsive means effective under certain operating conditions for disabling one of said pawls to allow advance of said carriage a plurality of character spaces during each cycle of movement of said member.
18. In a telegraph recorder, a plurality of recording elements collectively movable normally one character space, selecting means responsive to code signals and comprising a set of function levers, and means controlled by one of said function levers for causing said recording elements to advance by sustained movement through a plurality of spaces at a time from one recording position to another.
19. In a telegraph recorder, collectively movable recording elements, means for restraining the movement of said elements to one character space, code signal controlled means including a tabulator function lever, and means controlled by said function lever for disabling said restraining means to enable non-intermittent movement of said elements a predetermined plurality of character spaces at a time.
20. In a telegraph recorder, a movable type carriage, continuously rotatable means, means frictionally related to said means for imparting movement to said carriage, restraining means for rendering said carriage responsive during a portion of a revolution of said rotatable means, code signal controlled means including a tabulator function lever, and means controlled by said function lever for disabling said restraining

means to render said carriage fully responsive to rotation of said rotatable means.

21. In a recorder, a carriage movable to form character spaces, means to perform functions other than recording, a permutation device movable with said carriage to determine the character to be recorded, a stationary permutation device to control said means and said permutation device, and a tabulating device controlled by said means for controlling the advancement of said carriage a plurality of spaces at a time from one recording position to another.

22. In a telegraph printer, a carriage, spacing mechanism therefor, permutation code mechanism to control operations other than recording comprising a plurality of function code levers, and tabulating mechanism operative in response to the selective operation of a certain one of said levers to control the advancement of said carriage through a predetermined plurality of spaces at a time.

23. In a telegraph recorder, selector mechanism responsive to code signals, a carriage, spacing mechanism operative normally to control the advancement of said carriage one character space at a time, said mechanism embodying an escape-
ment device including a pair of pawls and means to bias said pawls attractively, and tabulating mechanism effective under control of said selector mechanism to disable one of said pair of pawls to control the advancement of said carriage through a plurality of spaces at a time. 5 10

24. In a telegraph recorder, selector mechanism, comprising a plurality of function levers, responsive to code signals, a type carriage, spacing mechanism operative normally to control the advancement of said type carriage one character space at a time, and tabulating mechanism effective under control of one of said function levers to control the uninterrupted advancement of said type carriage through a plurality of 15 20 spaces at a time.

ALBERT H. REIBER.
